US0D1006633S

(12) **United States Design Patent** (10) **Patent No.:** **US D1,006,633 S**
(45) **Date of Patent:** **** Dec. 5, 2023**

(54) **BOTTLE**

(71) **Applicant:** **The Nature's Bounty Co.,**
Ronkonkoma, NY (US)

(72) **Inventors:** **Simon Richard Gainey**, Media, PA
(US); **Jessica Keene**, Philadelphia, PA
(US); **Shelley Markoulis**, Wyckoff, NJ
(US); **Joel Nixon Thaikattil**, Bohemia,
NY (US)

(73) **Assignee:** **The Nature's Bounty Co.,**
Ronkonkoma, NY (US)

(**) **Term:** **15 Years**

(21) **Appl. No.:** **29/774,192**

(22) **Filed:** **Mar. 15, 2021**

(51) **LOC (14) Cl.** **09-01**
(52) **U.S. Cl.**
USPC **D9/574**

(58) **Field of Classification Search**

(57) **CLAIM**

The ornamental design for a bottle, as shown and described.

DESCRIPTION

FIG. 1 is an isometric top view of a bottle showing our new design.

FIG. 2 is an isometric bottom view of the bottle.

FIG. 3 is a front elevation view of the bottle.

FIG. 4 is a right side elevation view of the bottle.

FIG. 5 is a rear elevation view of the bottle.

FIG. 6 is a left side elevation view of the bottle.

FIG. 7 is a top plan view of the bottle; and,

FIG. 8 is a bottom plan view of the bottle.

The broken lines shown in the drawings are for the purpose
of illustrating parts of the article that form no part of the
claimed design.

1 Claim, 7 Drawing Sheets
